(57) **CLAIM**

The ornamental design for a full-face respirator mask as shown and described.

DESCRIPTION

FIG. 1 is a top perspective view of a full-face respirator mask, according to the present design.

FIG. 2 is a front elevation view of the full-face respirator mask of FIG. 1.

FIG. 3 is a rear elevation view of the full-face respirator mask of FIG. 1.

FIG. 4 is a right-side elevation view of the full-face respirator mask of FIG. 1.

FIG. 5 is a left-side elevation view of the full-face respirator mask of FIG. 1.

FIG. 6 is a top plan view of the full-face respirator mask of FIG. 1; and,

FIG. 7 is a bottom plan view of the full-face respirator mask of FIG. 1.

The broken lines shown in the drawings depict portions of the full-face respirator mask that form no part of the claimed design.
